UNITED STATES PATENT OFFICE.

DONALD S. BARROWS, OF ROCHESTER, NEW YORK, ASSIGNOR, BY MESNE ASSIGNMENTS, TO THE SYMINGTON COMPANY, A CORPORATION OF MARYLAND.

DRAFT-RIGGING BACKSTOP.

Application filed December 30, 1921. Serial No. 525,873.

To all whom it may concern:

Be it known that I, DONALD S. BARROWS, a citizen of the United States, residing at Rochester, in the county of Monroe and State of New York, have invented certain new and useful Improvements in Draft-Rigging Backstops; and I do hereby declare the following to be a full, clear, and exact description of the invention, such as will enable others skilled in the art to which it appertains to make and use the same.

My invention relates to draft rigging backstops which are secured between the center sills or draft sills of a railway car to provide means for transmitting to the car underframing the buffing shocks to which the draft rigging is subjected in service.

The principal object of the invention is to produce a backstop of great strength and simple form which is comparatively light in weight and may be readily attached to the car sills with small expenditure of labor.

The principal feature of the invention, generally stated, consists in forming a backstop with side walls adapted to be secured to the car sills and with a forward end wall which is united to said side walls and is adapted to form an abutment for a movable part of the draft rigging, and in bracing and supporting said end wall by means of a plurality of rearwardly divergent vertical webs disposed between the said side walls and integrally united at their forward ends to the said end wall.

A further feature of the invention consists in forming the backstop with side walls and with a forward end wall constituting an abutment for a movable part of the draft rigging, and in supporting the said end wall against buffing shocks by means of a plurality of rearwardly divergent webs which are spaced from said side walls and are united at their forward ends to said end wall, a plurality of parallel vertical webs being respectively united to the rear ends of said divergent webs and extending rearwardly therefrom.

Another feature of the invention consists in forming a backstop with side walls and with a forward end wall united to said side walls and adapted to afford an abutment for a movable part of the draft rigging, and in supporting the said end wall against buffing shocks by means of a horizontal web extend-

ing between said side walls and united at its forward end to said end wall, the said backstop being also provided on opposite sides of the said horizontal web with a plurality of rearwardly divergent vertical webs which are united at their forward ends to the said end wall and are also united to the horizontal web.

A still further feature of the invention resides in forming the backstop with side walls, an end wall adapted to constitute an abutment for a movable part of the draft rigging, a horizontal web united at its forward end to said end wall, and a centrally disposed vertical web united at its forward end to said end wall, and in also providing the backstop with rearwardly convergent vertical webs or flanges which are integrally united to said centrally disposed web and to said horizontal web.

Other features of the invention residing in special details of construction and in the relations of structural parts, will hereinafter appear.

In the drawings illustrating the invention, the scope whereof is pointed out in the claims,

Figure 1 is a view, partly in plan and partly in horizontal section, of a portion of a railway car having a backstop involving the invention applied thereto, a well known type of draft rigging being shown as associated with the backstop.

Figure 2 is a view, partly in side elevation and partly in vertical section, of the construction shown in Figure 1.

With the exception of the backstop, none of the features of construction invented by me and disclosed in the drawings is claimed in the present application. The draft rigging, which is of a well known type and which is chosen merely for the purpose of illustration, without intending to restrict the backstop to use in conjunction therewith, is formed with a yoke 1 between the arms of which a pair of spaced follower blocks, 2 and 3 respectively, is mounted in a well known manner. Dot and dash diagonal lines 4 diagrammatically represent a yielding cushioning unit interposed between the said followers, while 5 indicates the car coupler. The buffing shocks to which this special form of draft rigging is subjected in service are communicated to the backstop by the en-

gagement of the rear end of the draft yoke 1 with the forward end of said backstop.

The spaced center sills or draft sills 6 of the car underframe may be of any desired 5 form.

The backstop is formed with longitudinally extending side walls 7 which are respectively adapted to engage the inner faces of the adjacent sills 6, the said side walls 10 preferably being provided with three vertically spaced horizontally extending rows of openings for receiving rivets 8 whereby the structure may be securely attached to the car sills. The outer ends of the side 15 walls 7 preferably converge forwardly, as indicated at 9, and are united by a transversely extending end wall 10 forming an abutment for a movable part of the draft rigging, the said movable part in the present instance being the draft yoke 1.

United to the end wall 10, preferably midway of its height, is a horizontal web 11 which may advantageously extend rearwardly sufficiently far to be integrally connected to a vertically disposed hollow column 12 adapted to receive a king bolt (not shown), the said horizontal web preferably being the full width of the backstop between the side walls 7 thereof and being integrally joined to the latter. In the neighborhood of the king bolt column 12 the side walls 7 of the backstop are preferably also tied together by means of transversely extending vertical flanges 13 which radiate from and are integrally united to said column. The side walls 7 are also connected adjacent the king bolt column by a floor plate or base plate 14 adapted to transmit the weight of the car to a center bearing (not shown); and a top plate 15 integrally uniting the upper edges of the side walls 7 to the column 12 may also be employed if desired.

United at its forward end to the end wall 10 is a centrally disposed vertical web 16 which is integrally joined to the horizontal web 11 and projects in opposite directions therefrom. The rear end of the web 16 is preferably directly united to the king bolt column 12, as shown, and may be extended vertically at its rear end so as also to unite with the base plate 14 and the top plate 15. The forward portion of the centrally disposed web 16 is preferably of the same, or substantially the same, height as the end wall 10.

The end wall 10 is braced and supported against buffing shocks by a plurality of rearwardly divergent vertical webs 17 disposed between the side walls 7 on opposite sides of the horizontal web 11, the said divergent webs being united at their forward ends to the said end wall and being cast integral with the said horizontal web. As clearly shown in Figure 2, it is preferred that the divergent webs 17 shall be formed, at points

adjacent said end wall, with sloping portions 18, resulting in increasing their height in the neighborhood of the end wall 10.

The divergent bracing webs 17 are respectively united at their rear ends to spaced longitudinally extending vertical webs 19 which extend rearwardly toward the transverse web 11 with which they are preferably connected. The vertical webs 19 are spaced from the side walls 7 and from the central web 16 and preferably extend on opposite sides of the horizontal web 11 for a distance less than the height of the said side walls. At their points of junction with the parallel webs 19, the rearwardly divergent webs 17 are united by rearwardly convergent vertical webs or flanges 20 which are integrally connected to and project from opposite sides of the horizontal web 11 and which preferably extend from the centrally disposed vertical web 16 to the respective side walls 7 of the backstop.

What I claim is:—

1. A draft rigging backstop involving side walls adapted to be secured to spaced car sills, a forward end wall united to said side walls and adapted to form an abutment for a movable part of the draft rigging, a plurality of rearwardly divergent webs united at their forward ends to said end wall, and webs extending at an oblique angle to the longitudinal axis of said backstop for uniting said divergent webs.

2. A draft rigging backstop involving side walls adapted to be secured to spaced car sills, a forward end wall united to said side walls and adapted to form an abutment for a movable part of the draft rigging, a horizontal web united to said end wall and extending rearwardly therefrom, and a plurality of rearwardly divergent webs on opposite sides of said horizontal web united to the latter and to said end wall.

3. A draft rigging backstop involving side walls adapted to be secured to spaced car sills, a forward end wall united to said side walls and adapted to form an abutment for a movable part of the draft rigging, a plurality of vertical webs connected at their forward ends to said end wall and diverging rearwardly therefrom, a plurality of parallel vertical webs respectively united to the rear ends of said divergent webs and extending rearwardly therefrom, webs uniting said divergent and parallel vertical webs at a point in the rear of said end wall.

4. A draft rigging backstop involving side walls adapted to be secured to spaced car sills, a forward end wall united to said side walls and adapted to form an abutment for a movable part of the draft rigging, a web united at its forward end to said end wall and extending rearwardly therefrom, and a plurality of rearwardly divergent webs disposed between said side walls on

opposite sides of said rearwardly extending web and united to the latter and to said end wall, said divergent webs being of maximum height adjacent said end wall and being reduced in height rearwardly of said wall.

5. A draft rigging backstop involving side walls adapted to be secured to spaced car sills, a forward end wall united to said side walls and adapted to form an abutment for a movable part of the draft rigging, a horizontal web extending between said side walls and united thereto and to said end wall, and a plurality of rearwardly divergent vertical webs disposed between said side walls on opposite sides of said horizontal web, said divergent webs being united at their forward ends to said end wall and being united to said horizontal web and being of decreasing height rearwardly from said end wall.

6. A draft rigging backstop involving side walls adapted to be secured to spaced car sills, a forward end wall united to said side walls and adapted to form an abutment for a movable part of the draft rigging, a horizontally disposed web united to said side walls and united at its forward end to said end wall, and a plurality of vertical webs united to said horizontal web and extending on opposite sides thereof, said vertical webs being spaced from said side walls and extending on opposite sides of said horizontal web for a distance less than the vertical extension of said side walls from said horizontal web.

7. A draft rigging backstop involving side walls adapted to be secured to spaced car sills, a forward end wall united to said side walls and adapted to form an abutment for a movable part of the draft rigging, a centrally disposed longitudinally extending vertical web connected at its forward end to said end wall and extending rearwardly therefrom, a plurality of vertical webs united at their forward ends to said end wall and extending rearwardly therefrom obliquely to the longitudinal axis of said backstop in spaced relation to said side walls on opposite sides of said centrally disposed web, and webs uniting said vertical webs at a point in the rear of said end wall.

8. A draft rigging backstop involving side walls adapted to be secured to spaced car sills, a forward end wall united to said side walls and adapted to form an abutment for a movable part of the draft rigging, a centrally disposed vertical web connected at its forward end to said end wall and extending rearwardly therefrom, a plurality of vertical webs united at their forward ends to said end wall and extending rearwardly therefrom obliquely to the longitudinal axis of said backstop in spaced relation to said side walls on opposite sides of said centrally disposed web, said vertical webs rearwardly of

said end wall being of less height than said centrally disposed web, and webs uniting said vertical webs at a point in the rear of said end wall.

9. A draft rigging backstop involving side walls adapted to be secured to spaced car sills, a forward end wall united to said side walls and adapted to form an abutment for a movable part of the draft rigging, a plurality of rearwardly divergent webs united at their forward ends to said end wall and extending rearwardly therefrom, a plurality of longitudinally extending vertical webs respectively united to said divergent webs and extending rearwardly therefrom, and vertical webs extending between and uniting said divergent webs at their points of junction with said vertical webs and to the side walls.

10. A draft rigging backstop involving side walls adapted to be secured to spaced car sills, a forward end wall united to said side walls and adapted to form an abutment for a movable part of the draft rigging, a centrally disposed vertical web united at its forward end to said end wall and extending rearwardly therefrom, and rearwardly convergent webs extending between and united to said centrally disposed web and said side walls.

11. A draft rigging backstop involving side walls adapted to be secured to spaced car sills, a forward end wall united to said side walls and adapted to form an abutment for a movable part of the draft rigging, a centrally disposed horizontally extending web united at its forward end to said end wall, a centrally disposed vertical web united at its forward end to said end wall and extending upon opposite sides of said horizontal web and integrally united thereto, and vertical webs disposed between and spaced from said central vertical web and said side walls and united to said horizontal central web.

12. A draft rigging backstop involving side walls adapted to be secured to spaced car sills, a forward end wall united to said side walls and adapted to form an abutment for a movable part of the draft rigging, a horizontal web united at its forward end to said end wall and extending rearwardly therefrom, a centrally disposed vertical web united at its forward end to said end wall and extending rearwardly therefrom, and vertical webs extending obliquely to said centrally disposed web and said side walls and integrally united to said centrally disposed web and to said horizontal web.

13. A draft rigging backstop involving side walls adapted to be secured to spaced car sills, a forward end wall united to said side walls and adapted to form an abutment for a movable part of the draft rigging, a vertically extending hollow column adapted

to receive a king bolt, a horizontal web
united at its forward end to said end wall
and extending rearwardly therefrom and
united to said hollow column, a centrally
5 disposed vertical web united at its forward
end to said end wall and extending rear-
wardly therefrom and united to said hollow

column, and rearwardly divergent vertical
webs united to and extending upon opposite
sides of said horizontal web and united at 10
their forward ends to said end wall.

In testimony whereof I affix my signa-
ture.

DONALD S. BARROWS.
